United States Patent Office

Des. 188,832
Patented Sept. 13, 1960

188,832

LETTER TRAY

Armer R. Staebell, Wooster, Ohio, assignor to Rubbermaid Inc., Wooster, Ohio, a corporation of Ohio

Filed Feb. 15, 1960, Ser. No. 59,405

Term of patent 14 years

(Cl. D74—9)

FIG. 3

FIG. 4

Fig. 1 is a front perspective view of a letter tray showing my new design;

Fig. 2 is a side elevational view thereof, the side opposite thereto being similar in appearance;

Fig. 3 is a top plan view; and

Fig. 4 is a front elevational view thereof as it appears with parts broken away for convenience of illustration.

I claim:

The ornamental design for a letter tray or similar article, substantially as shown and described.
